UNITED STATES PATENT OFFICE

2,076,483

SPRINKLER HEAD FOR AUTOMATIC SPRINKLER SYSTEMS

Arthur C. Rowley, Drexel Hill, Pa., assignor to
Globe Automatic Sprinkler Company, Philadelphia, Pa., a corporation of Pennsylvania

Application October 25, 1935, Serial No. 46,799

3 Claims. (Cl. 169—37)

This invention relates to improvements in sprinkler heads for automatic sprinkler systems, and the principal object of the invention is to provide a sprinkler head frame of novel and improved construction which can be manufactured at materially lower cost and will be generally more efficient than the frames made in accordance with the prior practices.

Frames of this character commonly comprise spaced arms which at one end are attached to the body of the sprinkler head and which in effect form a supporting yoke for a deflector element located in the path of the stream of water projected from the said body, the function of this deflector being to disperse and spread the water over a relatively large area. Such frames heretofore have been in the form of castings, with the deflector element being formed as a separate part. These prior frames not only had the disadvantage of relatively high cost of manufacture but were relatively inefficient, in that the cast support frequently interfered with the efficient operation of the deflector.

The primary objects of the present invention, therefore, are to reduce the cost of manufacture of frames of this character, and at the same time to provide a frame which is generally more efficient in the respects hereinafter set forth than the frames of the prior art.

30 In the attached drawing:

Figure 1 is an elevational view of a frame made in accordance with my invention showing the manner of its attachment to the body of the sprinkler head;

35 Fig. 2 is an enlarged front elevation of the completed frame;

Fig. 3 is a side elevational view of the frame;

Fig. 4 is a top plan view of the frame, and

40 Fig. 5 is a view of the sheet metal blank from which the frame is produced.

The frame made in accordance with my invention is produced as an integral structure from sheet metal, the initial step consisting in forming a flat blank from the metal sheet by a simple stamping operation. This blank comprises a mid section 1 of roughly circular form, the peripheral portion of which consists of an annular series of radially projecting tongues 2. Extending from the outer ends of adjoining pairs of the tongues, 45 designated by the reference characters 2a, 2a, at diametrically opposite sides of the mid section 1 are arms 3, 3, said arms having outwardly diverging side edges 4, 4, and each terminating at their outer ends in rectangular terminal portions 5.

55 As illustrated, the circular mid section is provided

with apertures 6 arranged in spaced relation around the center.

The flat blank described above is partially formed to the finished shape by means of a stamping operation, which involves the pressing of the central portion of the mid section 1 from the normal plane of the latter to produce a central conical projection 7 on one face of the mid section and a corresponding concavity on the other face, the apertures 6 lying on the inclined sides 10 of this central conical projection. Also and as clearly illustrated, the tongues 2 and 2a are turned down or depressed toward that face of the mid section from which the cone 7 projects. In this operation also the arms 3, including the terminal portions 5, are bent to channel form, said channel decreasing in depth toward and terminating approximately at the outer ends of the tongues 2a from which, as previously described, the said arms extend.

In succeeding operations, the channeled arms 3 are bent into substantial parallelism with each other and substantially perpendicular to the normal plane of the mid section 1, and the longitudinal edges of the channeled terminal portions 5 of the arms are brought together, thereby giving said terminal portions a roughly cylindrical form. The said terminal portions are then machined externally to true cylindrical shape suitable for insertion in cylindrical sockets or openings formed 30 for their reception in the body of the sprinkler head, as shown in Fig. 1.

In assembling the frame with the body of the sprinkler head, the cylindrical end portions 8 of the arms are passed through the openings 9a in lugs 9 projecting from opposite sides of the body 10 of the sprinkler head. The portions 8 of the frame are sufficiently greater in length than the thickness of the lugs 9 to permit the riveting or upsetting of the ends, as indicated at 8a in Fig. 1, 40 to thereby rigidly and efficiently secure the frame to the body of the sprinkler head.

The frame is characterized by simplicity of form and manufacture and neatness of appearance. It is also highly efficient in the water-deflecting 45 function, in that the deflector portion is substantially symmetrical throughout, and that surface of the deflector presented to the water stream is entirely unobstructed, this by reason of the fact that as described the supporting arms merge 50 into the outer ends of the depressed deflecting tongues 2a.

There may be some modification in detail without departure from the invention.

I claim:

1. A sheet-metal frame for sprinkler heads comprising a mid section of roughly circular form constituting a deflector, and integral supporting arms extending from opposite sides of said deflector, said arms having a substantially U-shaped cross section throughout the major portion of their lengths and having each a cylindrical terminal end portion for attachment to the body of the sprinkler head.
2. A sheet-metal frame for sprinkler heads comprising a mid section of roughly circular form having a pressed-out substantially conical center portion at the under side, the peripheral portion of said mid section consisting of a series of outwardly projecting tongues and said tongues being turned down to form with said conical center a concaved deflecting surface at the said under side

of the mid section, and integral supporting arms joining the outer ends of tongues at opposite sides of the mid section and extending away from said mid section at the under side, and means at the outer ends of said arms for attaching the frame to the body of the sprinkler head. 5

3. A frame for sprinkler heads consisting of an integral sheet-metal structure comprising a liquid-deflecting and distributing mid section, supporting arms extending from the edges of said mid section, said arms being shaped throughout the major portions of their lengths to longitudinal channel form, and each arm having a cylindrical extremity constituting means for attaching the frame to the body of the sprinkler 10 head. 15

ARTHUR C. ROWLEY.
